UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

DRILL-STEEL RETAINER.

1,355,806.

Specification of Letters Patent. Patented Oct. 19, 1920.

Application filed March 22, 1920. Serial No. 367,834.

To all whom it may concern:

Be it known that I, LEWIS C. BAYLES, a citizen of the United States, residing at Easton, in the county of Northampton and State of Pennsylvania, have invented a certain new and useful Improvement in Drill-Steel Retainers, of which the following is a specification.

This invention relates to drill steel retainers of the type in which a yoke embraces the steel and is suitably held or clamped in position upon the front head of the tool.

The primary object of the present invention is to produce a yoke retainer so constructed that if it is struck by the collar of the drill steel for instance as the steel comes forward, the yoke tends to bind instead of being thrown outwardly away from the steel.

Another object of the invention is to secure a retainer which is conveniently adjusted and held by spring pressed means independent of the side bolt springs.

Further objects will hereinafter appear and the drawings illustrate a preferred form of the invention in which—

Figure 1 is a side elevation of the front end of a tool partly broken away and partly in vertical section on the line 1—1 of Fig. 2 showing my improved retainer and

Fig. 2 is a side elevation at right angles to Fig. 1.

Referring to the drawings, A represents a portion of the cylinder casing of a fluid actuated percussive tool, in this instance a rock drill being illustrated having the front head B within which the drill steel C is adapted to be inserted. The front head B is held to the cylinder casing A as by means of the usual spring pressed side bolts D.

The drill steel or tool retainer is shown in the form of a yoke E adapted to embrace the drill steel and provided with hook shaped ends F adapted to be seated in suitable means for retaining the yoke upon the tool.

In accordance with the present invention recessed portions G are provided at each side of the front head and spring pressed cup shaped supports H are arranged within said recessed portions for coöoperating with the tool retainer or yoke E. The location and arrangement of the recessed portions G and cup shaped supports H are such that the points of contact between the hook shaped ends F of the yoke E and the sup-

ports H are offset from the longitudinal axis of the tool as indicated more particularly in Fig. 1, so that as the retaining yoke E is forced or sprung into the position shown in full lines in Fig. 1 it will be automatically retained in such position, even if struck by the collar J of the drill steel as the steel comes forward. Any such blow upon the yoke retainer E would tend to cause the retainer to bind more tightly on the drill steel 65 rather than assume the position indicated in dotted lines in Fig. 1. This construction substantially overcomes one of the disadvantages or defects of yoke retainers which are apt to spring away from the steel on impact. 70

For clamping the yoke retainer E in position on the tool the hook shaped ends F are preferably formed with flattened portions K and L and the cylinder casing A is provided with lugs or flanges O adapted to co-operate with the retainer yoke E and permit the yoke E to be clamped between the lugs O and the cup shaped supports H.

The cup shaped supports H may, if desired, be provided with extensions or plungers P surrounded by the springs Q for guiding and centering the supports H. As shown, the plungers P may extend through the apertures R in the ends of the recessed portions G for guiding the plungers. The 85 guiding shanks or extensions could be omitted if desired.

In assembling the parts of the retainer, the springs Q are inserted in the recessed portions G from the top and the cup shaped supports with their shanks are also placed in the recessed portions G from the top. The retainer yoke E may then be quickly adjusted and clamped in position as indicated in Fig. 1.

I claim—

1. A drill steel retainer comprising in combination with the front head of the tool, oppositely-located recessed portions at the sides of the front head, yielding supports in said recessed portions having cup shaped sockets offset from the longitudinal axis of the tool, and a retainer in the form of a yoke having hook shaped ends adapted to be seated in said cup shaped sockets under projections 105 on the tool casing.

2. A drill steel retainer, comprising in combination with the tool casing, front head and spring pressed side bolts, of oppositely located recessed portions at the sides of the 110

front head, spring pressed cup shaped supports in said recessed portions and independent of the side bolt springs, a retainer in the form of a yoke adapted to embrace the drill steel and having hook shaped ends adapted to be seated in said cup shaped supports under projections on the tool casing, the points

of contact between said yoke ends and the cup shaped supports being offset from the longitudinal axis of the tool. ¹⁰

In testimony whereof, I have hereunto set my hand.

LEWIS C. BAYLES.
